FOUNTAIN PEN

Filed Dec. 24, 1928

UNITED STATES PATENT OFFICE

JAMES LLOYD H. WILSON, OF WESTBORO, ONTARIO, CANADA

FOUNTAIN PEN

Application filed December 24, 1928. Serial No. 328,153.

This invention relates to a fountain pen designed to provide facilities for varying the writing fluid, so that a plurality of various coloured inks may be used.

5 The principal object is to provide a simple means for feeding various coloured inks to the nib-flow channel.

A further object is to provide a means for cutting off the flow through the other fluid ducts while permitting a flow through one 10 fluid duct of the coloured ink desired.

A further object is to provide a means for filling or emptying each sack individually.

With the foregoing and other objects in 15 view as will appear as the description proceeds, the invention consists of the novel construction, combination and arrangement of co-operating elements as more specifically set forth, claimed and shown in the accompanying drawings forming a part of the present 20 application, in which:

Fig. 1 is a longitudinal detail view of a fountain pen embodying the principles of my invention, part being shown in section and 25 part being broken away.

Fig. 2 is a sectional view taken on the line 2—2 of Fig. 1, the nib being removed.

Fig. 3 is an enlarged view of a section of 30 the pen, showing in detail the ink-flow control member.

Fig. 4 is a transverse sectional view taken on the line 4—4 of Fig. 1.

Fig. 5 is an end view of the pen looking directly on towards the point of the nib.

35 Fig. 6 is a perspective view of a modified form of the ink-flow control member.

Like numerals of reference designate corresponding parts throughout the different views.

40 7 is the fountain pen barrel, preferably of cylindrical formation. The forward end of this barrel, as at 8, is provided exteriorly with threading to accommodate any suitable cap. Extending forwardly of the threaded portions 45 8 is an annular extension 9, provided with a longitudinal slot extending inwardly from the outer periphery as at 10. 11 is a plug, the inner end of which is adapted to be refitted securely into the forward end of the barrel 7. The outer end of this plug may be of

any desired formation on its outer contour. Protruding inwardly from the inner end of the plug 11, I provide nipples 12 and 14. I do not wish to be limited to the particular shape of these nipples as they may be of any 55 desired shape to accommodate the ink sacks 15 and 16 respectively, which sacks may be annular, oval, semi-circular or of any other desired shape in cross section to best serve the purpose for which they are designed. In 60 the drawing, Fig. 4, these sacks are shown as of oval shape in cross section. 17 is a partition plate extending longitudinally between the sacks 15 and 16. When the plug 11 is properly positioned in the barrel 7, the end 65 of this partition plate 17 engages in a transverse slot formed on the inner end of the plug 11. Adjacent each sack is provided a means for compressing the same. This invention does not relate to the specific structure of a 70 means for compressing the sacks and therefore any desired means for compressing the sacks may be used in connection with the construction disclosed in this invention. In the accompanying drawings, I show a lever 18 75 fulcrumed to the barrel 7, the inner end of which moves the compression plate 19 to compress its respective sack when the lever is operated.

20 is the nib plug which may be of any desired shape or design such as now or may be used for assisting in the supporting of the nib in a plug similar to the plug 11. This nib plug 20 may be formed as an integral part of the plug 11 or it may be separate with its inner end fitted securely in an opening formed 80 inwardly from the forward end of the plug 11. In the construction disclosed, this nib plug 20 is shown as an integral part and has formed therearound an annular guideway designed 85 to receive and retain the inner end of the nib 21 between the nib plug 20 and the plug 11. This nib plug 20 is provided with a nib-flow channel 22, extending longitudinally on the upper portion thereof. In the plug 11, I provide inflow ducts 23 and 24, extending from the inner ends of the nipples 12 and 14 respectively and converging to a common meeting point 25 adjacent to and in direct communication with the nib-flow channel 22. 95

The plug 11 is provided with a slot 26 formed inwardly, preferably from the left side thereof, to intersect the ink-flow ducts 24 and 23. 27 is an ink-control member reciprocally positioned in the slot 26 and in snug relationship to the surrounding portion of the plug 11. A portion adjacent the upper end of the ink-control member is reduced, as at 28, and the upper end 29 bent preferably at right angles to the body portion of the ink-control member 27. The ink-control member 27 is provided with openings 30 and 31 spaced a pre-determined distance apart, so that when the ink-control member 27 is in its full seated position, the opening 31 will register in alignment with the ink-flow duct 24, while when the ink-control member 27 is pulled outwardly until its shoulder contacts with the inner contour of the annular extension 9, the opening 30 will register in alignment with the ink-flow duct 23. When the plug 11 is being fitted into the forward end of the barrel 7, the ink-control member 27 is positioned in the opening 26 and the reduced portion 28 positioned opposite the open end of the slot 10. When the plug 11 is then pushed farther into the open end of the barrel 7, the ink-control member 27 is locked against displacement but may be reciprocated in the opening 26 (the reduced portion 28 working through the slot 10) to alternate the flow of inks through either the ink-flow ducts 23 and 24 as desired. The bent end 29 of the ink-control member provides a means whereby a finger nail or any thin edged article may be inserted thereunder to raise the same outwardly from the annular extension 9.

Referring to the modified form, Fig. 6, I provide an ink-control member 27^a, which is practically the same as the ink-control member 27 hereinbefore described, with the exception that I provide a single opening as at 32 instead of the spaced openings 30 and 31. When the ink-control member 27^a is in full seated position, the opening 32 would register in alignment with the ink-flow duct 23, while when raised to full pulled-out position, the opening 32 would be in alignment with the ink-flow duct 24.

In the construction disclosed, I have shown only two sacks 15 and 16, with two nipples 12 and 14 to which the sacks are fitted and ink-flow ducts 23 and 24 through which different coloured inks will flow from the respective sacks. I do not wish to limit myself to providing a pen structure which is provided with means for writing with only two different coloured inks. It will be readily appreciated that additional sacks, additional nipples and additional ink-flow ducts may be provided to accommodate a greater number of coloured inks. Therefore, the foregoing specification and annexed drawings disclose the preferred embodiment of my invention, but it is to be understood that minor changes

may be resorted to in the commercial adaptation of my invention without departing from the scope of the invention as hereinafter claimed.

What I claim as new is:

1. A fountain pen comprising a barrel; a plug, having its inner end normally fitted securely in the forward end of said barrel; a nib plug carried by the forward end of said plug; a nib-flow channel formed in said nib plug; a nib retained on said nib plug over said channel; a plurality of nipples carried by the inner end of said plug; ink sacks carried by said nipples; a partition between said sacks; an individual ink-flow duct extending from each respective nipple, which ducts converge to a common meeting point adjacent to and in communication with the inner end of said nib-flow channel and a means reciprocally mounted transversely in said plug for individually controlling the flow of ink through said ink-flow ducts. 70

2. A fountain pen comprising a barrel; a plug, having its inner end normally fitted securely in the forward end of said barrel; a nib plug carried by the forward end of said plug; a nib-flow channel formed in said nib plug; a nib retained on said nib plug over said channel; a plurality of nipples carried by the inner end of said plug; ink sacks carried by said nipples; a partition between said sacks; an individual ink-flow duct extending from each respective nipple, which ducts converge to a common meeting point adjacent to and in communication with the inner end of said nib-flow channel; an ink-control member reciprocally mounted transversely in said plug to intersect said ink-flow ducts, said member having formed there-in openings at a predetermined distance apart so that said openings may be brought (one at a time) into registered alignment with its respective ink-flow duct and a means for limiting the outward movement of said member. 100

3. A fountain pen comprising a barrel; a plug, having its inner end normally fitted securely in the forward end of said barrel; a nib plug carried by the forward end of said plug; a nib-flow channel formed in said nib plug; a nib retained on said nib plug over said channel; a plurality of nipples carried by the inner end of said plug; ink sacks carried by said nipples; a partition between said sacks; an individual ink-flow duct extending from each respective nipple, which ducts converge to a common meeting point adjacent to and in communication with the inner end of said nib-flow channel; a means for individually controlling the flow of ink through said ink-flow ducts, which means consists of a control plate reciprocally mounted transversely in said plug to intersect said ink-flow ducts, said plate permitting the flow of ink from one duct therethrough when said 110

control plate is in its innermost position and
from the other duct when in its outermost
position and a means for limiting the ad-
justment of said plate to provide the desired
ink flow therethrough.

5 In testimony whereof, I affix my signature.

JAMES LLOYD H. WILSON.
